J. A. B. SMITH

TYPEWRITING MACHINE

Filed June 16, 1919

UNITED STATES PATENT OFFICE.

JESSE A. B. SMITH, OF STAMFORD, CONNECTICUT, ASSIGNOR TO UNDERWOOD TYPE-WRITER COMPANY, OF NEW YORK, N. Y., A CORPORATION OF DELAWARE.

TYPEWRITING MACHINE.

Application filed June 16, 1918. Serial No. 304,532.

To all whom it may concern:

Be it known that I, JESSE A. B. SMITH, a citizen of the United States, residing in Stamford, in the county of Fairfield and

5 State of Connecticut, have invented certain new and useful Improvements in Typewriting Machines, of which the following is a specification.

This invention relates to typewriting machines, and is herein disclosed as applied to an Underwood standard typewriting machine.

The invention is herein disclosed as embodied in a device adapted to facilitate the 10 simultaneous entering of single items upon a bill head and a ledger sheet, and more especially adapted for use in such work where a single item only is entered daily on each bill and the ledger sheet.

20 In order to facilitate making such entries, it is advantageous to have an end gage which is adapted to be positioned in the machine, so that a work-sheet, for example a bill, may be gaged thereagainst, in a predetermined 25 position and so that another work-sheet, for example a ledger sheet, may be gaged against another end gage settable with reference to the first gage, thus enabling the sheets to be inserted with a minimum of 30 labor, conducing to accuracy and rapidity of work.

In order to enable a typewriting machine used for this work to be also used for other purposes, it has been found advantageous to 35 provide a special paper table at the rear of the platen, forward from the usual paper table in spaced relation thereto and adapted to carry the gage for the work-sheet, and so positioned as to guide the work-sheet down 40 to the platen and yet be out of the way of work-sheets inserted in the typewriting machine on the usual paper table for ordinary writing. As herein disclosed, the end gage on such a secondary table is provided with 45 clips which are adapted to lightly hold the work-sheet, and with a short side gage which serves to gage the side edge of the work-sheet. The feed rolls may be utilized for the other end gage.

50 Other features and advantages will hereinafter appear.

In the accompanying drawings,

Figure 1 is a perspective view of an Underwood standard platen frame or shift frame, showing my invention as applied thereto.

55 Figure 2 is an enlarged section of the end gage, and the means whereby it is adjusted.

Figure 3 is a sectional side view of the parts shown in Figure 1, and showing a 60 ledger sheet positioned.

Figure 4 is a view similar to Figure 3, but showing the feed-rolls effective, and a bill gaged against them.

65 Figure 5 is a view similar to Figure 4, but showing the ledger sheet and the bill advanced to the printing point.

A work-sheet 10, which may be a ledger sheet, is passed around the platen 11, which is journaled in the ends 12 of the usual Underwood shift frame, by being slipped down 70 over a paper-guide which may be a second paper table 13, mounted upon brackets 14 springing from the ends 12 of the shift frame and lying between the platen 11 and the usual rear paper table 15. The paper table 13 may be considerably narrower than 75 the platen 11 and rear paper table 15, and advantageously extends down below the cross piece 16, which is fast to it and which supports it upon the brackets 14. The paper 80 table 13, as clearly seen in Figures 3 and 4, terminates considerably short of the platen 11, and above the point where the usual paper table 15 terminates, thus leaving a 85 clear space between the two tables for the insertion of ordinary work-sheets.

When the work-sheet 10 is slipped down upon the paper table 13, it strikes the lower 90 end 17 of the paper table 15, and is bent forwardly to pass between the usual rear feed roll 18 and the platen 11, and from thence swings forwardly above the front feed roll 19, up past the printing point indicated in Figure 5 to the point at which the lower- 95 case types 20 strike against the work-sheet. When inserted in this manner, the trailing edge of the work-sheet 10 may be gaged against a transverse bar member forming an end gage 21, which is formed as an L on a 100 plate 22, said plate being adjustably fastened to the platen by means of thumb-nuts

23, which are adapted to be screwed up upon screws 25 extending through openings 24 in the table 13, to draw down the plate 22 upon the face of the table. When thus adjusted, 5 the work-sheet 10 is gaged at its trailing edge by moving the work-sheet upwardly against the end gage 21, gaging it beneath a pair of lightly pressing spring clips 26, which bear upon the front of the table 13 or 10 upon a front extension 27 of the plate 22.

The work-sheet 10 may be further gaged at this time by means of the side gages 28, which are shown as formed of turned-up ends of the extension 27. In order to facilitate 15 the rapid centering of the work-sheet 10, the lower ends 29 of the side gages 28 may flare outwardly, and to enable the work-sheet 10 to be easily handled, the side gages 28 may be only just long enough to give a 20 good bearing for the edge of the work-sheet.

The feed-rolls 18 and 19 may now be drawn against the platen by operating the usual casting-off handle 32. When a work-sheet has been thus adjusted and is held 25 in place by the clips 26 and feed-rolls 18 and 19, a second work-sheet 30, in the form of a bill head, together with a carbon 31, may be inserted, usually between the work-sheet 10 and the platen 11, as shown in Figure 4, although obviously if desired the work-sheet 30 and carbon 31 may be inserted, in proper relation, at the back of the second paper table 13 and on the usual paper table 15, which forms a part of the 30 usual platen frame having the ends 12. The work-sheet 30 may be passed downwardly until it seats itself against the bite of the rear feed-rolls 18, which, in this way, form a leading edge gage for the second work-sheet. When the work-sheets have been thus brought to the proper position relatively to each other by rolls or gages 18 and the gage 21, the platen may be rotated forwardly either by actuating the 35 usual line-space mechanism, which includes the line-space wheel 33, or by rotating the knob 34 until the line to receive the typewritten matter is at the printing point where the types 20 can write upon it. It is to be noted that the rear feed-rolls 18 may 40 serve as a leading-edge gage for a work-sheet inserted from the rear at the front of either of the paper tables 13 to 15.

Owing to the fact that the clips 26 hold 45 the first work-sheet lightly, the two work-sheets advance together to the printing point at the turning of the platen. After the desired line of writing has been written, the work-sheets are removed from the machine, and another first and second work-sheet 10 and 30 are inserted in the same manner.

It will be observed that the device is of especial utility where entries are to be made 50 at a distance from the top of a large num-

ber of ledger sheets 10, the distance varying from time to time, but being identical for a large number of sheets at any one time. According to the present invention, the end 70 gage 21 may be adjusted to suit this distance, viz, the distance from the end gage 21 to the writing line upon the bill 30, when the latter is gaged against the feed-rolls 18.

To facilitate the rapid and accurate adjustment of the end gage 21, a suitably 75 graduated scale 35 may be provided at each end of the table 13, the graduations being co-ordinated with the position of the line to receive the printing upon the bill head 30 when the latter is gaged against the feed-rolls 18.

Variations may be resorted within the scope of the invention, and portions of the improvements may be used without others.

Having thus described my invention, I 85 claim:

1. In a typewriting machine, the combination with a rotatable platen and a directrix to guide an ordinary work-sheet inserted at the introductory side of the platen to the bottom of the platen, of means for collating a plurality of superposed sheets at the introductory side of the platen preparatory to feeding them around the bottom of the platen to typing position, said collating means comprising leading-edge gaging means in the form of feed-rolls to run on the bottom of the platen, a collating table above the usual path of ordinary work-sheets introduced between the directrix and the platen, said collating table directing collated work-sheets to said directrix to be guided thereby beneath the platen, and an adjustable trailing-edge gage on said collating table for variably collating an outer sheet of said plurality in proper registration with an inner work-sheet gaged at its leading edge by said gaging feed-rolls. 90

2. In a typewriting machine, the combination with a revoluble platen and a rear paper table adapted to accommodate work-sheets, of an upstanding narrower secondary table between the rear table and the platen, an adjustable rear end gage upon said secondary table, a clip mounted upon said gage and adapted to hold the bottom of a work-sheet passed around the platen and gaged upon said narrower table, a side gage also mounted upon said end gage, and a feed roll adapted to be made effective to 100 clamp the work-sheet against the platen and to serve as a leading end gage for a second work-sheet. 110

3. In a typewriting machine, the combination with a revoluble platen, of a paper table behind the platen, an adjustable end gage upon said table, flaring side gages adjacent said end gage leaving most of the side of the table open, and a feed roll adapted to clamp against the platen a work-sheet 125 130

upon said table, and also adapted to serve as a leading edge gage for another work-sheet between the first work-sheet and the platen.

4. In a typewriting machine, the combination with a revoluble platen, of a paper table behind the platen, a secondary paper table between the first paper table and the platen, an adjustable end gage upon said secondary table, flaring side gages adjacent 10 said end gage leaving most of the side of the table open, and a feed roll adapted to clamp against the platen a work-sheet upon said table, and also adapted to serve as a leading edge gage for another work-sheet 15 between the first work-sheet and the platen.

5. In a typewriting machine, the combination with a revoluble platen and a paper table behind the platen, of a plate comprising an end gage adapted to be adjustably 20 fastened upon said table, clips upon said plate adapted to lightly clip a work-sheet upon the table, and short side edge gages upon said plate leaving most of the table edge clear for the insertion of the work- 25 sheet.

6. A typewriting machine for typing upon either an ordinary work-sheet or collated sheets, comprising the combination with a rotatable platen, of sheet-controlling 30 means at the introductory side of the platen comprising a paper-table for receiving and guiding an ordinary work-sheet, a second or collating table at the introductory side of the platen, forward of the first paper-table and having its lower edge spaced therefrom to avoid interference with the use of the first paper-table for receiving and guiding said ordinary work-sheet, a feed-roll for clamping work-sheets on the 40 platen, said feed-roll forming a gage for the leading edge of a collated work-sheet thrust downwardly back of the platen and overlying a second collated work-sheet on the collating table, and an adjustable gage carried 45 by the collating table for gaging the trailing edge of the second collated work-sheet thereon.

7. In a typewriting machine, the combination with a rotatable platen, of a paper table behind the platen, a second paper table between the first paper table and the platen, an end gage adjustable on the second paper table for gaging the trailing edge of a work-sheet, short side gages for the second paper 55 table adjacent to said end gage and leaving the greater part of the sides of the second paper table open, and a feed roll for clamping on the platen the work-sheet on the second table and forming an end gage for the leading edge of another work-sheet.

8. In a typewriting machine, the combination with a rotatable platen and a paper table behind the platen, of a second paper table between the first paper table and the platen, a transverse bar member adjustably

mounted on the second table and forming an end gage for the trailing edge of a work-sheet, spring-pressed clips carried by said bar member for lightly pressing against the work-sheet to hold it in place on the second table while permitting it to be fed forward around the platen, short side gages carried by said bar member and leaving the greater part of the sides of the second table open for the insertion of the work-sheet, and a feed roll for holding the work-sheet on the platen and forming an end gage for the leading edge of a second work-sheet. 70

9. A typewriting machine for typing upon either an ordinary work-sheet or collated sheets, comprising the combination with a revoluble platen and a directrix to guide an ordinary work-sheet to the bottom of the platen at the introductory side thereof, of means for collating sheets at the introductory 80 side of the platen preparatory to feeding them around the platen to typing position, said sheet-collating means comprising a collating table for guiding one of the work-sheets to be collated to the directrix and consequently to the bottom of the platen, said collating table terminating above the directrix so as not to interfere with the use thereof with ordinary work-sheets, a trailing-edge gage on said collating table for 85 variably gaging the trailing edge of the work-sheet thereon, and means at the introductory side of the platen for gaging the leading edge of a second collated work-sheet to adjust the latter relatively to the work-sheet in gaged position on the collating table. 90

10. In a typewriting machine, the combination with a cylindrical platen, of a paper-table adjacent thereto, and a sheet-positioning device adjustable on said table in a line-feeding direction, said device comprising a gage perpendicular to the table to gage the end of a work-sheet on the table, a flat portion extending along the table between the same and the gaged end of the work-sheet, and a clip for yieldably pressing the work-sheet against said flat portion to detain the work-sheet in position against the gage. 105

11. In a typewriting machine, the combination with a cylindrical platen, of a paper-table adjacent thereto, and a sheet-positioning device adjustable on said table in a line-feeding direction, said device comprising a gage perpendicular to the table to gage the 110 end of a work-sheet on the table, a flat portion extending along the table between the same and the gaged end of the work-sheet, short side gages for positioning the work-sheet on said flat portion, and a clip for 115 yieldably pressing the work-sheet against said flat portion to detain the work-sheet in position against the first-mentioned gage. 120

12. In a typewriting machine, the combination with a cylindrical platen, of a paper- 125

table adjacent thereto, and a sheet-positioning device adjustable on said table in a line-feeding direction, said device comprising an end gage perpendicular to the table, a clip on said gage for yieldably pressing the gaged end of a work-sheet toward the table, and a member extending between the table

and the gaged end of the work-sheet to cooperate with the clip to grip and detain the work-sheet in position against said gage.
